IRONING MACHINE

Stanley F. Bickell, Frampton Cotterell, and
Harold E. Jackson, Liverpool, England

Application April 28, 1952, Serial No. 284,748.

21 Claims. (Cl. 38—61)

1

This invention relates to ironing machines intended mainly for domestic use and particularly to machines of the type having a rotatable roll supported at one end only and a heated pressing shoe which can be moved into and out of engagement with the roll.

It is an object of the present invention to provide an ironing machine having an improved mechanism which is simpler than known mechanisms, and which is easily controlled by an operator.

According to the present invention an ironing machine comprises a rotatable roll, a shoe capable of movement into and out of engagement with the roll, driving means, a drive output member operatively connected with the driving means, a first clutch which transfers motion from the drive output member to roll driving means only on rotation of the drive output member in one direction, a second clutch which transfers motion from the drive output member to shoe actuating means only when the drive output member is rotating in the opposite direction, and control means operable to change the direction of rotation of the drive output member.

In one embodiment of the invention a mechanism is provided whereby the second clutch is rendered inoperative after the shoe has engaged the roller or has completed the disengaging movement therefrom.

According to a feature of the invention the driving means consists of an electric motor and the direction of rotation of the drive output member is changed by reversing the direction of rotation of the electric motor. The motor may be of the single phase capacitor started type with three star connected windings which are energized according to the desired rotation by means of a switch operatively linked to the control means.

An ironing machine according to the invention will now be described in greater detail by way of example with reference to the accompanying drawings of which,

Figure 1 is a front elevation of the ironing machine mounted upon a cabinet stand;

Figure 2 is a cross section through the roll and its mounting;

Figure 3 is a rear elevation of the shoe separated from the ironing machine;

Figure 4 is a part section on the lines A—A of Figure 3;

Figure 5 is a plan view of part of the operating mechanism;

Figure 6 is a section on the lines B—B of Fig. 5 but with the motor removed;

2

Figure 7 is a cross section through one clutch assembly on an enlarged scale,

Figure 8 is an end view of the mechanism shown in Fig. 5,

Figure 9 is a cross section on the line C—C of Fig. 8 but with the motor removed,

Figure 10 shows part of the shoe operating mechanism on an enlarged scale,

Figure 11 is an enlarged view of part of the control arm,

Figure 12 shows the pedal control mechanism, and

Figure 13 is a circuit diagram of the motor control circuit.

Referring to Figure 1 of the drawings it will be seen that the ironing machine itself is of conventional appearance and has a padded rotatable roll 1 supported at one end only on a hollow goose neck or standard 2 containing roll driving gears. A heatable shoe 3, which in Figure 1 is just visible behind the roll 1, is mounted so that it can move into and out of engagement with the roll 1. The goose-neck 2 is mounted on a base 4 which in Figure 1 is shown supported on a cabinet stand 5 which enables an operator to sit whilst controlling the machine by means of a foot pedal indicated generally by the reference numeral 6.

As can be seen in Figure 2 the roll 1 consists of a hollow tube 7 covered by a layer or padding 8 in turn covered by a cloth sleeve 9. The roll is rotatably supported by discs 10 and 11 on a tube 12 which is secured cantilever fashion in the goose-neck 2. The roll 1 is rotated by a driving rod 13 coupled to the tube 7 by a further disc 14. The rod 13 passes through the tube 12 as shown and is coupled to a spindle 15 of a gear 16 forming part of a gear train 16, 17, 18, 19 mounted on a bracket 20 inside the goose-neck 2.

The shoe 3, shown in more detail in Figures 3 and 4, is mounted midway of its ends on a bracket 21 and has the usual concave metallic pressing surface 22. Flexible leads 23 connect the shoe heating element 24, seen in cross section in Fig. 4, with the main electric circuit in the base 4 of the machine. The temperature of the shoe is preset by a rotatable control member 25 which forms part of thermostat mechanism of any convenient type mounted within the structure of the shoe. The face of the control member 25 is suitably inscribed with a temperature scale so that the required temperature can be preset accurately.

The driving mechanism for both roll and shoe is mounted within the base 4 of the machine and

is shown in plan view in Figure 5. An electric motor of the single phase capacitor started type with three star connected windings is mounted within a casing 26 bolted to a housing 27 which contains a reduction gearing and clutches by means of which the drive from the electric motor can be used to rotate the roll 1 or to operate the shoe 3.

A pinion 28 fixed on the shaft of the electric motor meshes with a gear wheel 29 whose axle carries a pinion 30 engaging a gear wheel 31 which, with a pinion 32, is mounted on a stub shaft carried by the casing 27. A main gear 33 which meshes with the pinion 32 incorporates two roller clutches and, dependent upon the direction of rotation of the gear 33, transmits rotation either to a gear wheel 34 engaging the gear wheel 19 in the goose-neck 2 and thus to the roll 1 or to a cam which operates the shoe 3.

Each face of the main gear 33 is formed with a concentric recess in which the roller clutches referred to above are mounted. From Figure 7, which shows a cross section through the left hand clutch as seen in Figure 6, it is clear that the clutch comprises a clutch centre 35, roller bearings 36, 37, 38 and 39 and a bearing cage 40. The roller bearings 36, 37, 38 and 39 co-operate with inclined surfaces 41, 42, 43 and 44 respectively formed on the periphery of the clutch centre 35. Leaf springs 45 and 46 are mounted in slots in the clutch centre 35. Each clutch centre has a central tubular extension 47 (Figure 6) and in the case of the right hand clutch as viewed in Figure 6 this extension 47 has the pinion 34 mounted on it. The extension 47 of the left hand clutch centre has a cam 48 secured to it. The cage 40 of the left hand clutch has secured to it the flanged end of a sleeve-like member 49 which fits over the extension 47 and carries a latch plate 50.

The clutches are arranged so that the right hand clutch will transmit the rotation of the main gear 33 to the pinion 34 only when the clutch is rotated clockwise by gear 33 (as viewed in the direction of arrow 51 in Figure 6). The left hand clutch transmits the rotation of the main gear 33 to the cam 48 only when rotated in an anti-clockwise direction and only then if the cage 40 is free to rotate. The roller bearings 38, 39 operate to transmit the anti-clockwise rotation of the main gear 33 to the clutch centre 35 while the rollers 36 and 37 serve to prevent the clutch centre running ahead of the main gear 33 which would result in an abrupt disengagement of the shoe and the roll.

Rotation of the cage 40 is controlled by the latch plate 50 which co-operates with the inturned end of a lever 52. These parts viewed in the direction of the arrow 51 are shown on an enlarged scale in Figure 10 and it will be seen that the latch plate 50 has a notch 53 and a projecting ear 54. The lever 52 is firmly secured at one end to a spindle 55 which passes through the housing 27 and carries outside the housing a lever 56 capable of turning the spindle. The lever 56 can also withdraw the spindle 55 through the medium of a pin 57 passing through the spindle, part way from the housing 27 against the action of a spring 58 (Figures 6 and 9).

The spring 58 normally holds the lever 56 against a plate 59 so that the lever abuts the in-turned edge 60 and a raised portion 61 of the plate 59 as is shown in Figure 9. The plate 59 has a slot 62 (Figure 8) cut in it and an adjustment plate 63 which is pivoted to the plate 59 at 64 and can be moved so as to mask the lower 75

part of the slot 62 as viewed in Fig. 8 and locked by a nut 66. A spring 65 is mounted between the lever 56 and the bottom of the plate 59. A control bar 66 is supported adjacent one end on the slot 62 and adjacent the other end on the bracket 67 in the base 4. The control bar 66 is capable of longitudinal movement, as will be described later, against the action of a spring 68 which is secured between the control bar and the base 4.

10 The spring 68 also exerts a vertical pull on the control bar 66. The end of the control bar 66 adjacent the plate 59 is shown on an enlarged scale in Fig. 11. This end is slotted and has two operating faces 69 and 70 which in the normal 15 operating position of the bar are vertical and a face 71 which has the same inclination with respect to the horizontal as an inclined part 72 on the lever 56. The slot in the control bar is also undercut as at 73 and 74 to form two horizontal 20 slots.

The control bar also has a small wedge shaped extension 75 (Figure 6). The wedge shaped extension 75 co-operates with a catch plate 76 mounted on a torsion bar 77 which extends laterally from the housing 27 parallel with the control bar. The torsion bar is journaled in the housing 27 and extends within the latter. One end of an arm 78 is fixed to the inner end of the torsion bar 77 inside the housing while the other end of the arm carries a roller 79 which is in contact with the surface of the cam 48 referred to above.

30 A sleeve 80 is fitted over the end of the torsion bar 77 remote from the housing 27 and is pinned to the bar at 81. The sleeve passes through a supporting bracket 82 and has a second bracket 83 clamped to it. The bracket 83 extends through the base 4 of the machine and is secured to the bracket 21 in the shoe 3.

One method of operating the control bar 66 40 is shown in Figure 12. The bar 66 carries a small stud 84 which is retained in contact with one arm of a bell crank lever 85 by the spring 86. The bell crank lever is pivoted at 86 in the base 4 and its other arm has an operating cable 87 coupled to it. This cable 87 passes down inside 45 the cabinet stand 5 and is attached to a foot pedal 88 which in Figure 12 is viewed in the direction of the arrow 89. The foot pedal is pivoted at 90 and has an over-travel stop 91.

Fig. 12 also shows how the end of the control bar 66 remote from the lever 56 can operate a switch 92 mounted beneath the base 4. This switch which is also shown diagrammatically in Figure 13 controls the power supply of the electric motor.

55 Referring now to Figure 13 which is a circuit diagram of the motor control, the motor windings W1, W2 and W3 are shown connected to the power supply terminal N, fixed contact 93 of the switch 92 and fixed contact 94 respectively. The 60 moving contact 95 of the switch is joined to the power supply terminal L. A capacitor C1 is connected across the ends of the windings W2 and W3. A switch operating plunger 96 transmits the motion of the control bar 66 to a flexible arm 97 carrying the contact 95. Fig. 13 shows the position of the flexible arm 97 when the pedal 88 is depressed by an operator.

70 Before describing the operation of the mechanism it will be assumed that the latter is in a position in which the shoe 3 is withdrawn from the roll 1. It follows, as will be appreciated later, that the projecting ear 54 of the latch plate 50 has engaged the in-turned end of the lever 52. Thus, the latch plate 50, sleeve 49 and cage 40

are prevented from rotating and thus the left-hand clutch is prevented from transmitting the rotation of the main gear 33 to the cam 48 which controls the rotation of the torsion bar 77. In addition, the movement of the torsion bar necessary to withdraw the shoe 3 has caused the catch plate 76 to move into the line of travel of the wedge-shaped projection 75 on the control bar 66 thus preventing the latter from further movement to the left as viewed in Figs. 5, 6 and 12. Thus the control bar cannot operate the switch 92 to produce a reversal in the direction of rotation of the electric motor and it follows that the roll 1 cannot be rotated as long as the shoe 3 remains withdrawn.

If now an operator wishes to iron, the foot pedal 88 is depressed fully and retained in that position. This movement of the pedal 88 is transmitted by the cable 87 and the bell-crank lever 85 to the control bar 66 which is moved to the right. The flexible movable member 97 of the switch moves to the position shown in Fig. 13 thus energising the motor to produce an anti-clockwise direction of rotation of the main gear 33. Face 69 of the slot at the end of the control bar 66 comes into contact with the lever 56 causing the latter to pivot on the projection 61 and so withdraw the spindle 55 from the housing 27 against the action of spring 58. This withdraws the inturned end of the lever 52 which disengages from the ear 54.

Spring 65 can now act on the lever 56 so that the latter moves clockwise as viewed in Fig. 8 and out of engagement with the face 69 at the control bar slot. Spring 58 is now free to return the lever 56 to the position shown in Fig. 9 and the lever 56 moves into the horizontal slot 73. Meanwhile, the disengagement of the inturned end of the lever 52 from the ear 54 has allowed the cage 40 to rotate with the main gear 33. As the main gear is rotating in an anti-clockwise direction the cam 48 is rotated and thus the torsion bar 77 is rotated by the lever 78 to bring the shoe 3 into engagement with the roll 1.

After approximately 150° of rotation the inturned end of the lever 52 engages the surface of the latch plate 50 and further rotation causes the lever 52 to rotate the spindle 55 and thus the lever 56 in an anti-clockwise direction so lifting the end of the control bar 66. Further rotation brings the notch 53 into line with the inturned end of the lever 52 and the spring 65 causes the spindle 55 to rotate slightly and the inturned end moves into the notch 53. This stops the rotation of the cage 40 and also movement of the shoe which has now engaged the roll 1. Furthermore, the lever 56 has been returned to the position from which it started.

During the movement of the shoe 3 into engagement with the roll 1 any attempt to return the control bar 66 to the left is prevented by one or other of the following circumstances according to the precise instant in the cycle at which the attempt is made:

1. The engagement of the inclined face 71 with the lever 56.

2. The engagement of the projection 75 on the control bar 66 with the catch plate 76 on the torsion rod 77.

3. Engagement of the face 70 with the lever 56.

The foot pedal 88 can now be released, thus allowing the control bar 66 to travel to the left under the action of spring 68. At the end of its travel, the bar 66 operates the switch 92 and the

flexible contact carrying member 97 moves so that the moving contact 95 engages the fixed contact 93 and the direction of rotation of the electric motor is reversed so that the main gear 33 can now rotate the gear 34 and thus the roll 1.

Depression of the foot pedal 88 subsequently first stops rotation of the roll 1 by reversing the direction of rotation of the electric motor and then by going through the sequence of events just described causes the shoe 3 to move away from the roll 1. It will be appreciated, of course, that the cam 48 is shaped to produce both the engagement with and the withdrawal from the roll 1 of the shoe 3.

The mechanism also allows an operator to carry out a pressing operation which involves movement of the shoe 3 into and out of engagement with the roll 1 without rotation of the latter. To achieve this, the foot pedal 88 is depressed fully thus reversing the switch 91 and the direction of rotation of the motor which brings the shoe 3 into engagement with the roll 1 as described above. The pedal 88 is then released and the spring 68 starts to move the control bar 66 back to the left. Complete movement to the left in the direction of arrow 89 is prevented as the inclined face 71 on the control bar 66 engages the corresponding inclined portion 72 of the lever 56. Thus, the end of the control bar follows the vertical movement of the lever 56 and the control bar cannot complete its leftward movement so as to cause, through a reversal of the rotation of the electric motor, rotation of the roll 1. Continued operation of the foot pedal in the manner just described causes the shoe 3 to engage and withdraw from the roll 1 without rotation of the latter.

Although in the embodiment described above a foot pedal control has been used, it will be appreciated that other forms of control may be adopted; for example, the control bar may be linked to a lever which is moved by the operator's knee.

The motor reversal means may, in an alternative embodiment, be replaced by a reversing gear interposed in the train of reduction gears between the motor and the drive output member, in which case the control means will actuate the reversing gear and the direction of rotation of the motor remains constant. In addition other suitable clutches may replace the roller type described above.

We claim:

1. An ironing machine comprising a rotatable roll, a shoe capable of movement into and out of engagement with the roll, driving means, a drive output member operatively connected with the driving means, roll driving means, a first clutch which transfers motion from the drive output member to said roll driving means only on rotation of the drive output member in one direction, shoe actuating means, a second clutch which transfers motion from the drive output member to said shoe actuating means only on rotation of the drive output member in the opposite direction and control means operable to change the direction of rotation of the drive output member.

2. An ironing machine comprising a rotatable roll, a shoe capable of movement into and out of engagement with the roll, driving means, a drive output member coupled to the driving means, roll driving means, a first clutch which transfers the rotation in one direction of the drive output member to said roll driving means, shoe

actuating means, a second clutch which transfers the rotation in the opposite direction of the drive output member to said shoe actuating means, a mechanism whereby the second clutch is rendered inoperative after the shoe has engaged the roll or has completed a disengaging movement therefrom and control means operable to change the direction of rotation of the drive output member.

3. An ironing machine according to claim 1 in which the driving means is an electric motor whose direction of rotation is controlled by the control means.

4. An ironing machine according to claim 3 in which the control means includes a control bar which is movable to operate a switch controlling the direction of rotation of the electric motor.

5. An ironing machine according to claim 4 in which the control means precludes more than one operation of the shoe actuating means following each operation of the control bar.

6. An ironing machine according to claim 5 in which the control bar has a slotted portion which cooperates with a first lever operatively connected with mechanism by which the second clutch may be rendered inoperative after the shoe has engaged the roll or has completed a disengaging movement therefrom.

7. An ironing machine according to claim 6 in which the second clutch includes a series of roller bearings which are mounted in a cage rotation of which is prevented by the mechanism when the second clutch is to be rendered inoperative.

8. An ironing machine according to claim 7 in which each clutch has a clutch centre having a central, tubular extension.

9. An ironing machine according to claim 8 in which the mechanism comprises a cam having a projection and a notch both of which can engage a second lever operatively linked with the first lever.

10. An ironing machine according to claim 9 in which the cam is secured to a sleeve fitting over the tubular extension of the clutch centre of the second clutch.

11. An ironing machine according to claim 10 in which the sleeve is also secured to the cage in which the roller bearings of the second clutch are mounted.

12. An ironing machine according to claim 11 in which the tubular extension of the clutch centre of the second clutch carries a member which engages a torsion bar operating lever and which is shaped so that successive rotations of

the member produce opposite movements of the operating lever.

13. An ironing machine according to claim 12 in which the tubular extension of the first clutch centre carries a pinion by means of which rotation of the drive output member is transmitted to the roll driving means.

14. An ironing machine according to claim 13 in which means are provided to prevent operation of the control means to produce rotation of the roll whilst the shoe is out of engagement with the latter.

15. An ironing machine according to claim 14 in which the shoe actuating means includes a catch plate which prevents operation of the control means to reverse the direction of rotation of the drive output member whilst the shoe is out of engagement with the roll.

16. An ironing machine according to claim 15 in which further means are provided which operate to prevent operation of the control means to produce rotation of the roll during movement of the shoe.

17. An ironing machine according to claim 6 in which the control bar at its slotted portion includes an inclined surface which co-operates with an inclined surface on the first lever to prevent movement of the control bar during part of the movement of the shoe.

18. An ironing machine according to claim 17 in which a further part of the slotted portion co-operates with the first lever to prevent movement of the control bar during another part of the movement of the shoe.

19. An ironing machine according to claim 18 in which the control means includes a foot pedal.

20. An ironing machine according to claim 19 in which following one mode of operation of the control means, the shoe is applied to the roll and the roll is held stationary, following another mode of operation of the control means the shoe is applied to the roll and the roll is then caused to rotate and following yet another mode of operation of the control means the shoe is withdrawn from the roll.

21. An ironing machine according to claim 1 in which the drive output member is coupled to the driving means through a reversing gear which is operated by the control means.
